UNITED STATES PATENT OFFICE.

DAVID PEPPER, OF PHILADELPHIA, PENNSYLVANIA.

MACHINE FOR CASTING THIN METAL CUPS.

Application filed August 15, 1921. Serial No. 492,359.

To all whom it may concern:

Be it known that I, DAVID PEPPER, citizen of the United States of America, and resident of the city and county of Philadelphia, in the State of Pennsylvania, have invented certain new and useful Improvements in Machines for Casting Thin Metal Cups, of which the following is a true and exact description, reference being had to the accompanying drawings, which form a part thereof.

My invention relates to mechanism for casting thin metal cups of the general type of the machine shown and described in my Patent No. 1,387,864 dated August 16, 1921.

The object of my present invention is to provide certain improvements in such mechanism and particularly I have in view a construction of the reservoir by means of which metal will be delivered into the molds in a small stream and the molds partially filled before they come into full registry with the reservoir. This device is for the purpose of avoiding the entrainment of air in the molds and for this purpose I also preferably provide for the escape of air from the mold before it comes into registry with the reservoir.

Another object which I have in view is the avoidance of a vacuum formed between the plunger and the closed end of the cup during the withdrawal of the plunger from the cup and a third object which I have in view is the utilization of compressed air delivered through the plunger into the closed end of the cup as a means for forcing the cup out of the casting mechanism.

The nature of my improvements for accomplishing the above mentioned purposes will be best understood as described in connection with the drawings in which they are illustrated and in which—

Figure 1 is a sectional elevation of a machine provided with my improvements taken as on the section line 1—1 of Fig. 2.

Figure 2 is a plan view of the mechanism shown on a smaller scale.

Figure 3 is a sectional plan view taken as on the line 3—3 of Fig. 1, and also shown on a smaller scale.

Figure 4 is a development showing the operation of the machine in the casting and stripping of the cups, and

Figure 5 is a diagrammatic sectional view showing a modification of the stripping device.

A indicates the machine standard here shown as of cylindrical form. A' is a cylindrical support for the turntable; A² a clamping ring for holding the table in position; A³ a top plate fitting on the standard A, as shown. B is the turntable, the outer edge of which is provided with teeth as indicated at B', said teeth being engaged by the driving gear C on the driving shaft C'. D is an annular ring secured to the table B and extending upward therefrom in which are formed evenly spaced cylinders as indicated at D'. E, E, etc., are the mold cylinders which fit in the cylindrical openings D' and rigidly held in place therein as by means of pins E². The molds proper are indicated at E' and below the molds the cylinders are formed with openings E⁴ of less diameter than the molds and in which fit the plungers. As shown, the lower ends of the openings E⁴ are closed by heads E² through which extend the actuating rods H to be hereafter described. F, F, etc., indicate the plungers working in the cylindrical bearings E⁴ and the upper ends of which have the form of the inside of the cup to be molded. These plungers are formed with longitudinal passages indicated at F' ending in a valve seat at the top of the plunger as indicated at F². F³ is a stop head secured to the lower end of the plunger and through which extends the actuating rod H. G, G, etc., are cylindrical bodies fitting and sliding in the longitudinal opening F' of the plungers and carrying at their upper ends valves G' adapted to seat themselves on the valve seats F². Slots or other openings, as indicated at G², are formed through the portions G to permit the free passage of air and this air passage is continued through the stop F³ so that air can pass freely through the longitudinal opening in the plunger at all times when the valve G' is not seated. H, H, etc., are actuating rods secured to the longitudinal slides G extending from the stop head F³ and the head E² and through the lower portion of the cylinder D' and further through openings B² in the turntable, the lower ends of the rods being formed with cam contacting surfaces as indicated at H² and H³ and pistons H' movable in the cylinders D' being attached to the intermediate portions of the rods H. K and K' are ports leading into the cylinder D' as indicated and connecting at proper parts in the travel of the

turntable with conduits K^2 and K^3 which are in communication with a source of pressure not shown and by which a fluid under pressure can be introduced when desired, either below or above the pistons H' so as to move them upward or downward. L , L' , etc., are ports leading into the longitudinal passages E^4 and, as shown, connecting with a conduit L' , where such connection is desired, whereby a source of air under pressure, not shown, can be connected to the passages E^4 .

I is a bracket or arm supported on the head A^3 of the standard and supporting or guiding the reservoir for fluid metal indicated at I' . The bottom I^2 of this reservoir rests upon the top of the ring D , as shown in Fig. 1, and is formed with an opening I , I^2 , through which it is in free communication with the molds lying below it. I^3 is a small passage formed in the bottom of the reservoir on the side to which the molds move and through which a thin stream of melted metal can flow into the mold, as shown in Fig. 4, before the mold comes into registry with the opening II^2 . As shown in Fig. 4, the opening I^3 ends in the shoulder I^5 and a further small opening I^4 is formed beyond this shoulder for the escape of air from a mold. J is a conduit for fluid metal by which it flows from a source not shown, into the reservoir I' and J' is an escape pipe for fluid metal by which the level of the metal in the reservoir is determined. As shown, I have indicated a heating coil at S , surrounding the reservoir by means of which the temperature of the metal therein can be held at the necessary high point.

At O and O' I have indicated heating coils for heating and maintaining the molds at a proper high temperature during a portion of their rotary travel and at P and P' I have indicated conduits which during certain parts of the travel of the molds may be used to cool them. N and N' are gutters for catching any fluid metal which may escape over the sides of the ring D ; N^2 indicating arms for supporting the inner gutter.

M , Fig. 2, indicates a knife or scraper secured to the standard and operating to wipe or cut off any metal which at this point may extend above the top of the mold.

At Q I have indicated the cast cup.

At R I have indicated a cam which at certain parts of the travel of the molds comes in contact with the cam contacting surface H^2 of the rods H to move them upward and at R' I have indicated the cam which at certain other points in the travel of the molds contacts with the contacting surfaces H^3 of the rods H and draws them downward.

In the modification of Fig. 5 I have shown a port E^5 leading into the bore E^4 of the mold cylinder E a short distance below the

mold proper E' . Air under pressure is admitted to the port E^5 from any convenient reservoir (none shown). The plunger F in this construction is solid and has a longer travel than in the previously described structure so that at desired times it is drawn down below port E^5 so that compressed air is admitted to the cup to force it out of the mold as indicated at the left of Fig. 5. r and r' are cams controlling the movements of the plungers in certain positions of the molds.

In operation empty molds with the plungers retracted through the bottoms of the molds and the valves G' open, as shown, at the right hand side of Fig. 4, approach the reservoir I' but before coming into registry with the reservoir or its opening I^3 the cam R comes into operation, lifting the rod H so as to close the port F^2 in the head of the plunger. With the port in this position the mold then comes into registry with the passage I^3 and a small stream of metal flows through this passage into the mold as indicated in Fig. 4, either partly or wholly filling it while the air contained in the mold is free to escape through the opening I^4 . Further movement of the mold brings it into full registry with the bottom opening II^2 , in the reservoir, and, at this time, fluid under pressure, preferably air, is admitted through a port K into the bottom of the cylinder D' and acting against the piston H' , raises it and the plunger rapidly to uppermost position of the plunger, the excess of metal contained in the mold being pushed back into the reservoir during the further travel of the molds.

At a point in the travel of the molds at which the cast cups have solidified it is next necessary to free them from the molding mechanism and according to my present invention I propose to use air under pressure as a means for forcing the molded cups out of the mechanism. In the preferred construction shown, I first retract the plungers from the inside of the cups and then utilize the force of compressed air to force the cups out of the molds. Preliminary to the retraction of the plunger the cam R' , as shown in Fig. 4, first pulls down the rod H , drawing the valve G' away from its seat F^2 , permitting the free flow of air, whether under pressure or not, into the space between the top of the plunger and the bottom of the cup so that when the plunger is further drawn down by the action, preferably, of the cam R' , as shown in Fig. 4, there is no vacuum formed in the bottom of the cup. The plunger having been fully withdrawn, as shown at the left hand side of Fig. 4, compressed air passing freely through the port F^2 forces the cup up out of the mold as indicated.

In such a modification as is shown in Fig.

5. The plunger F is moved from the position shown at the right of Fig. 5 to its uppermost position preferably by similar actuating mechanism to that above described 5 and, after the cast cup has solidified, it is drawn down out of the cup by the cam r' which also draws it down below port E^s to admit compressed air to blow the cup out of the mold.

10 Having now described my invention, what I claim as new and desire to secure by Letters Patent, is:

1. In a machine for casting thin metal cups comprising a series of molds, means for progressively moving the molds through a fixed path, plungers working in the molds and a reservoir for melted metal resting on top of the molds and having a bottom opening which registers with the molds as they 15 pass beneath it, the construction of the reservoir with a small channel formed in its bottom and located so as to register with the molds in advance of the main bottom opening of the mold.

25 2. In a machine for casting thin metal cups comprising moving molds and plungers working therein, the combination therewith of means for ejecting the cups from the molds consisting of ports whereby compressed air is admitted to the inside of the 30 cups and means for opening and closing said ports at definite points in the path travelled by the molds.

3. In a machine for casting thin metal 35 cups, comprising molds and plungers working therein, means for ejecting the cups, comprising an air channel formed through the plunger, means for admitting compressed air to said channels, a valve for opening and closing the air channel at the face of the 40 plunger and means for operating said valve.

4. In a machine for casting thin metal 45 cups, comprising molds and plungers working therein, said plungers having passages formed through them opening through the top of the plungers and having valve seats at the tops of said passages, in combination with means for introducing air to the plunger 50 passages, valves movable in the plunger passages from positions where they contact with the valve seats to retracted posi-

tions where they contact with stops in the plungers and means for moving the plungers through the valves working therein.

5. In a machine for casting thin metal 55 cups, comprising molds and plungers working therein, said plungers having passages formed through them opening through the top of the plungers and having valve seats at the tops of said passages, in combination with means for introducing air under pressure to the plunger passages, valves movable in the plunger passages from positions where they contact with the valve seats to retracted positions where they contact with 60 stops in the plungers and means for moving the plungers through the valves working therein.

6. In a machine for casting thin metal 65 cups, comprising molds and plungers working therein, said plungers having passages formed through them opening through the tops of the plungers and having valve seats at the tops of said passages, in combination with means for introducing air under pressure 70 to the plunger passages, valves movable in the plunger passages from positions where they contact with the valve seats to retracted positions where they contact with stops in the plungers, cams arranged to move the 75 valves to and from their seats and cylinders and pistons for moving the valves and through them the plungers rapidly into the molds.

7. In a machine for casting thin metal 80 cups, comprising molds and plungers working therein, said plungers having passages formed through them opening through the tops of the plungers and having valve seats at the tops of said passages, in combination with 85 means for introducing air under pressure to the plunger passages, valves movable in the plunger passages from positions where they contact with the valve seats to retracted positions where they contact with stops in the plungers, cams arranged to move the 90 valves to and from their seats and to retract the plungers from the molds and cylinders and pistons for moving the valves and through them the plungers rapidly into the 95 molds.

DAVID PEPPER.
